UNITED STATES PATENT OFFICE.

EUGENE IVINS, OF PHILADELPHIA, PENNSYLVANIA.

DESIGN FOR A CRACKER OR SIMILAR ARTICLE.

SPECIFICATION forming part of Design No. 23,078, dated February 20, 1894.

Application filed January 16, 1894. Serial No. 497,111. Term of patent 14 years.

To all whom it may concern:

Be it known that I, EUGENE IVINS, a citizen of the United States, residing at the city of Philadelphia, in the county of Philadelphia and State of Pennsylvania, have invented and produced a certain new and original Design for a Cracker or Similar Article, of which the following is a specification, reference being had to the accompanying drawing, showing a top or plan view of a cracker or similar article of my design.

The leading feature of my design consists of a cracker or similar article in the shape or form of a medallion, in which the characteristics thereof are the scalloping of the two sides *a* and *b*, in substantially the manner illustrated and the ridging at *c* and *c'*, and peaking in the middle at *d*, at the top and bottom of the cracker or similar article. The face *e*, of the article is punctured with small

holes in order to present an indented surface throughout the same, and the face at or about the middle of the cracker or similar article and lengthwise thereof is intended to have impressed therein or thereon in bold relief or otherwise the particular name under which it is to be known as an article of manufacture.

Having thus described the nature and objects of my design, what I claim as new, and desire to secure by Letters Patent, is—

The design for a cracker or similar article herein shown and described.

In testimony whereof I have hereunto set my signature in the presence of two subscribing witnesses.

EUGENE IVINS.

Witnesses:

THOMAS M. SMITH,
RICHARD C. MAXWELL.
